UNITED STATES PATENT OFFICE.

WILLIAM A. BATES, OF WINCHESTER, MASSACHUSETTS.

DESIGN FOR A HANDLE FOR SPOONS, &c.

SPECIFICATION forming part of **Design No. 20,576**, dated **March 10, 1891**.

Application filed January 24, 1891. Serial No. 378,978. Term of patent 7 years.

To all whom it may concern:

Be it known that I, WILLIAM A. BATES, a citizen of the United States, residing at Winchester, in the county of Middlesex, State of Massachusetts, have invented and produced a new and original Design for Handles for Spoons and other Table-Ware, of which the following is a specification, reference being had to the accompanying drawings, forming part thereof.

Figure 1 shows the face or obverse of my newly-designed handle, and Fig. 2 the reverse.

I have represented my newly-designed handle as applied to a spoon bowl, but it may be applied to other handles for table use.

The handle represented has been designed as a souvenir in commemoration of the landing of the Mayflower at Plymouth, Massachusetts, the historical incident of which is too well known to need description.

The handle *a*, within a suitable bead or

border *b*, represents a vessel, it being shown as afloat, the handle also showing, in a panel below or adjacent to the representation of the water, a figure of a rock.

25

The leading feature of my design, displayed at the face of the handle, is the vessel afloat and the rock, the reverse of the handle, inside the bead *b*, containing a representation, as *c c*, of the Mayflower or trailing arbutus, 30 while at *d* is shown a single flower of the same plant.

I claim—

The design for a handle for a spoon or other table-ware, as herein shown and described. 35

In testimony whereof I have signed my name to this specification in the presence of two subscribing witnesses.

WILLIAM A. BATES.

Witnesses:

GEO. W. GREGORY,
EDWARD F. ALLEN.
